(57) **CLAIM**

The ornamental design for bottle for liquids, as shown and described.

DESCRIPTION

The patent or application file contains at least one drawing executed in color. Copies of this patent or patent application publication with color drawing(s) will be provided by the Office upon request and payment of the necessary fee.

1.-3. Bottle for liquids

3.1 : Perspective

3.2 : Front

3.3 : Side view

3.4 : Top

The first alternative embodiment of the bottle for liquids is characterized by vertically oriented body tapering to the neck; base and cross section in the shape of an ellipse; and the ellipse hole with a deepening along the perimeter placed in the center of the upper part of the bottle. The second alternative embodiment is characterized by displacement of the hole to the right and a larger base and cross section of the body comparing to the first embodiment. The third alternative embodiment is characterized by smaller hole size comparing to the second embodiment.
